UNITED STATES PATENT OFFICE.

CHARLES J. NASH, OF CHICAGO, ILLINOIS, ASSIGNEE, BY MESNE ASSIGNMENTS, TO
WILLIAM H. MINER, OF CHICAGO, ILLINOIS.

DRAFT-RIGGING FOR SINGLE CENTER-SILL CARS.

1,093,797.

Specification of Letters Patent. Patented Apr. 21, 1914.

Application filed March 30, 1908. Serial No. 424,195.

To all whom it may concern:

Be it known that I, CHARLES J. NASH, a citizen of the United States, residing in Chicago, in the county of Cook and State of Illinois, have invented a new and useful Improvement in Draft-Rigging for Single Center-Sill Cars, of which the following is a specification.

My invention relates to draft rigging, and 10 more particularly to draft rigging designed for use on single center sill cars.

The object of my invention is to provide a draft rigging of a strong, simple, efficient and durable construction, which will be suitable for use on single center sill cars and which may be easily and conveniently applied, and which at the same time will have provision for lateral or side play of the draw-bar.

20 My invention consists in the novel construction of parts and devices, and in the novel combinations of parts and devices, by which this object or result is practically accomplished, the preferred embodiment of 25 the invention being shown in the accompanying drawing forming a part of this specification.

In said drawing, Figure 1 is a side elevation partly in vertical longitudinal section 30 showing a single center sill car draft rigging embodying my invention, one of the members of the draft yoke being removed to better show the other parts. Fig. 2 is a plan view partly in central longitudinal horizontal section. Fig. 3 is an enlarged cross section on line 3—3 of Fig. 2. Fig. 4 is a detail perspective view of the front draw-bar and yoke connecting block. Fig. 5 is a detail perspective view of the combined rear follower and draw-bar yoke key. Fig. 6 is a perspective view of one of the members of the draw-bar yoke. Fig. 7 is a cross section on line 7—7 of Fig. 1 and Fig. 8 is a section on line 8—8 of Fig. 1 the rear follower being omitted.

In the drawing, A represents the center sill of a car of the kind having a single center sill directly in line with the draw-bar B.

50 C C are the two limbs or members of a horizontally disposed draw-bar yoke, each preferably a steel forging.

D is the connecting block between the yoke C and draw-bar B, and E a horizontally disposed flat key extending through the draw-bar B, yoke C and connecting block D.

The central upright web *a* of the center sill A is furnished with a front recess, pocket or cut-out portion A¹ to receive the draw-bar B and front connecting block D, and also with a rear recess, pocket or cut-out portion A² to receive the front and rear followers F F¹ and the cushioning devices of the draft rigging, the two recesses or pockets A¹ A² being separated by an intervening bridge or connecting portion *a'* of said center sill web *a*.

G G are combined center sill web-reinforcing and draft-lug members secured in pairs on opposite sides of the center sill web *a* surrounding the recess or pocket A² therein. 70 Each of the combined center sill web-reinforcing and draft-lug members D is preferably of cast metal and furnished with an integral transversely extending limb or member G¹, each preferably corresponding in width to the width of the bridge member *a'* of the web *a* between the recesses or pockets A A¹. Each of the web reinforcing and draft lug members G is preferably of angle form in cross section and adapted to fit the web *a* and flange *a'* of the center sill A. The web-reinforcing and draft-lug members G on opposite sides of the web are connected thereto by rivets *g* which extend through said members G G and the center sill web. 80 The web-reinforcing and draft-lug members G are secured to the center sill web around the recess or pocket A² and are so arranged that their meeting ends or faces *g*¹ *g*² break joints with each other. The angle shape of the members G in cross section give them 90 an extended horizontal bearing against the upper and lower ends of the draft rigging followers F F¹.

The draw-bar and yoke connecting block 95 D is furnished with a four sided or walled socket *d* at its front end to receive the rear end of the draw-bar and to which said draw-bar is removably connected by the front key E. The connecting block D is provided with curved or rocker bearing faces *d*¹ for engagement with the horizontally disposed yoke members C C and thus permit the draw-bar B to have a limited lateral play in respect to the yoke as required, to enable the 100 cars to properly pass around curves. At its rear end, the connecting block D is furnished with a vertical slot or recess *b*² to receive the bridge or connecting member *a'* of the center sill web *a* and the cross limbs G¹ 110

2
of the web-reinforcing and draft-lug members G which are secured one on each side of said web bridge a^1 ; and this slot or socket d^2 is furnished with curved or flaring upright 5 sides or walls d^3 to provide for the lateral play or swinging movement of the draw-bar B and connecting block D. The key E by which the draw-bar B and connecting block D are connected to the yoke members C C 10 is furnished with cotters e.

The center sill-web-reinforcing and draft-lug members G are furnished with suitable stops for the followers to abut against, the 15 number of these stops corresponding to the number of followers that are employed in the draft rigging. As illustrated in the drawing, the cushioning devices of the draft rigging are of a kind requiring only two followers, a front and rear one, and the 20 draft lugs or stop shoulders on the members G are consequently only four in number, namely, a front one g^3 , a rear one g^4 , and two intermediate ones g^5 and g^6 to limit the compression of the springs or movement of 25 the cushioning devices employed. The rear follower F^1 is preferably furnished with integral key devices f for connecting the rear ends of the yoke members C C, the rear follower being thus a combined follower and yoke connecting key. It is preferably furnished with abutment shoulders f^1 for the inner faces of the yoke members C to fit against and with removable cotters f^2 which extend through the rear ends of the 30 yoke members C and the key member f which fits in the slot C^1 of the yoke member C.

The cushioning device of the draft rigging may be of any suitable kind or construction. It, however, preferably comprises a longitudinally movable friction shell H, friction blocks H^1 , wedge block H^2 , anti-friction rollers h between the inclined or wedging faces of the wedge block and the 45 friction blocks, and a spring or springs H^3 H^4 within the friction shell H, and a preliminary compression block or follower H^5 interposed between the rear follower F^1 and the springs H^3 H^4 , the latter to provide for 50 the better cushioning of the lighter blows or less violent movements of the draw-bar.

K K are guides, preferably of cast metal, having faces K^1 for engagement with the friction shell H and having arms K^2 , shaped 55 to fit the outer faces of the web reinforcing and draft lug members G G and the upper face of the lower flange a^2 of the center sill A and connected thereto by a clamp bolt K^3 which extends through said guide members 60 K, and said members G and the center sill. The friction shell H is furnished with

guide wings or arms h^1 that fit between the corresponding upright faces of the yoke members C C. The connecting block D is preferably furnished with ribs d^4 and preferably shaped as illustrated in the drawing. 65

M M are guiding bars or wearing plates, preferably of angle bar form in cross-section, secured to the center sill web A below the front pocket A^1 to give a broad bearing 70 for the connecting block D to slide upon. These angle bars M also serve to reinforce the center sill web A at the front end. The draw-bar B is of the ordinary standard Master Car Builders' construction and the 75 socket d in the connecting block D is shaped to receive the rear end of such draw-bar. The connecting block D is furnished with a rounded or beveled face d^5 at its rear end to bring its point of contact with the follower F as near the center or middle of the follower as practicable and to permit the draw-bar to swing laterally without canting or tilting the follower. 80

I claim:—

1. In a draft rigging, the combination with the draw-bar, of a draw-bar yoke and a connecting block having a socket to receive the rear end of the draw-bar, and rocker faces for engagement with the limbs 90 of the draw-bar yoke to allow for lateral play of the draw-bar, said connecting block having at its rear end an upright slot to receive a bridge member of a center sill web and the crosslimbs of center-sill-web-reinforcing members, the walls of said rear slot being curved to allow for lateral play of the draw-bar, substantially as specified.

2. In a draft rigging, a draw-bar and draw-bar yoke connecting block having a 100 socket to receive the rear end of the draw-bar, rocker faces for engagement with the draw-bar yoke and a rear slot or recess to receive a center sill web member and center sill web reinforcing members, substantially 105 as specified.

3. In a draft rigging, a center sill having a portion of its central web cut out to form a pocket to receive draft rigging followers and cushioning devices, and provided with 110 combined web reinforcing and draft lug members secured to said web and surrounding said pocket at sides and ends, said reinforcing and draft lug members being secured on both sides of said center sill web and said 115 members breaking joints with each other at their meeting ends or faces, substantially as specified.

CHARLES J. NASH.
